UNITED STATES PATENT OFFICE.

JOSEPH W. OBERBECK, OF ST. LOUIS, MISSOURI, ASSIGNOR OF ONE-HALF TO CHARLES A. WINSTON, OF BOWDEN, OKLAHOMA.

GRIPPING TOOL FOR ENGAGING AND PULLING PUMP RODS.

Application filed August 13, 1923. Serial No. 657,047.

This invention relates to an improvement in gripping devices and has for its primary object the purpose of providing an improved tool which can be lowered within a casing or 5 tubing of an oil well for engaging and withdrawing a broken pump rod or the like.

Another object of the invention is to provide a gripping device which when engaged within a depending casing and forced down- 10 wardly therein will engage the rod to be pulled, and when forced in the opposite direction will firmly grip the rod.

Another object of the invention is in providing an improved engaging and gripping 15 device with detachable guiding means for adapting the device or tool to be used in casings of different sizes.

Other and further objects will appear in the specification and be specifically pointed out 20 in the appended claims, reference being had to the accompanying drawings, exemplifying the invention, and in which:-

Figure 1 is a vertical section taken through this improved gripping device and showing 25 the same depended within an oil well casing, ready for operation upon a broken pump rod.

Figure 2 is an enlarged horizontal section taken on the line II—II of Fig. 1.

30 Figure 3 is an enlarged horizontal section taken on the line III—III of Fig. 1.

Figure 4 is a fragmentary view of the lower end of this improved gripping device showing a different guiding ferrule mounted 35 on the forward end thereof, for properly guiding the gripping device as it is being lowered within a relatively large casing, the casing being shown in section.

Referring by numerals to the accompanying 40 drawings, this improved gripping device is comprised of a tubular member 1 which is threaded exteriorly as designated at 2 at the forward end and mounted on said exterior threads is a guiding ferrule 3, said ferrule 45 having a centrally arranged opening 4 to which leads an inverted funnel shape mouth 5.

The tubular member 1 is provided with an 50 annular tapering wall 6 adjacent its forward end, said wall tapering inwardly to the opening 4 of the ferrule 3, as clearly shown in Fig. 1.

The upper end of the tubular member 1 is 55 provided with interior threads 7 and for engagement with said threads is the threaded

end 8 of a shank 9, said shank having a flat sided portion 10 formed intermediate of its ends, and formed on said shank in opposite disposition to the threaded end 8 is a threaded extension 11 which is extended 60 from a shoulder 12.

Reciprocably mounted within the tubular member 1 is a block 13 having an extending tapered end 13^a and extended horizontally from said tapered end is a plurality of supporting pins 14 each being for the support of a depending gripping jaw 15.

Each of the jaws 15 is preferably made of hardened tool steel and is each provided with an opening 16 adjacent its upper end, 70 each opening of each jaw being for the reception of a respective pin 14, the lower end of each jaw being provided with a plurality of teeth 17, each jaw having an engaging face 18 which is adapted to bear against the 75 annular tapered wall 6 of the tubular member 1, as shown in Fig. 1.

A coil spring 19 is located within the tubular member 1 and interposed between the threaded end 8 of the shank 9 and the block 80 13.

As already set forth in the objects of this invention, the theme thereof is to provide a device which may be lowered in an oil well casing for the purpose of engaging and withdrawing a pump rod which has been broken. In the operation of oil wells, it quite frequently happens that a pump rod may break several hundred feet below the ground surface, and it is quite often a very 90 tedious matter to provide a connection with the broken rod at such a great depth. This improved device is therefore applicable.

In the operation of the device, legs or 95 lengths 20 each having a coupling end 21 are connected together, the lowermost end being connected with the threaded extension 11 of the shank 9, and the device is then lowered into the well casing 22.

During the lowering of the gripping device, the guiding ferrule 3 will hold the tapering mouth 5 thereof in approximate concentric position with the tubing so that when the broken end of the pump rod such as designated at 23 is engaged by the 100 tapered mouth 5, it will be forced from the inner wall of the tubing by said tapered mouth so that the opening 4 of the gripping device will engage over the upper end of the 105 pump rod. The upper extending end of 110

the rod upon being engaged within the opening 4 will engage the tapered faces 24 of the gripping jaws 15, thereby forcing the said jaws upwardly along with their supporting block 13, said block compressing the coil spring 19. This forcing upwardly of the jaws 15 along the tapered wall 6 will cause the toothed ends of said jaws to swing outwardly, and when they have swung outwardly a distance far enough to accommodate the diameter or thickness of the pump rod 23, the upper end of said pump rod will be engaged surroundingly by the toothed ends of said jaws.

15 After the upper broken end of the pump rod has become engaged by the toothed ends of the gripping jaws 15 and the end of the rod has abutted against the extending end 13^a of the block 13, further descending of the gripping device is stopped, and the device is ready to be elevated.

As upward pulling movement is applied to the pulling device, the coil spring 19 will force the supporting block 13 downwardly and as the tubular member 1 of the gripping device is continued on upwardly the tapering wall 6 will engage the outer face 18 of each of the jaws 15 thereby firmly forcing the teeth of said jaws against and around the upper end of the pump rod so that the pump rod will be firmly secured by the jaws, and as the gripping device is moved on upwardly said jaws will become firmly locked and the pump rod will be withdrawn upwardly in 35 the casing.

After the pump rod has been successfully pulled from the well casing, the gripping jaws are released from the end of the rod by pressing downwardly on the tubular member 1 in which the block 13 will be forced upwardly by the rod thereby releasing the jaws 15 from engagement with the rod in which the gripping ends of the jaws will be swung outwardly. If, however, the jaws will not 40 release the rod, the shank 9 is removed from the upper end of the tubular member and the spring 19 removed and a threaded member is engaged in the threaded opening 25 which is provided in the block 13 so that said block 45 can be pulled upwardly from the tubular member 1, said block carrying the gripping jaws 15 and the upper end of the pump rod therewith. When the gripping jaws 15 are removed from the tubular member 1, it is 50 obvious that said jaws can be readily released from their positions of gripping with the pump rod.

This improved device can be used for different sizes of well casing and in this connection a suitable diameter guiding ferrule 26, as shown in Fig. 4, can be secured to the forward end of the tubular member 1^a, said ferrule 26 having a tapered mouth 27 for receiving and guiding a pump rod which may 55 be leaning against the side wall of the cas-

ing through the central opening 28 of the ferrule 26.

What I claim is:

1. A gripping device comprising a tubular member, a supporting block located in 70 said member, a plurality of gripping jaws reciprocable within said member secured to the lower end of said block, means provided whereby said jaws are swung away from one another as they are moved in one direction, 75 said jaws adapted to be moved inwardly towards each other when moved in the opposite direction, said block being provided with a centrally disposed opening for the reception of a drawing-out tool.

2. A gripping device comprising a tubular member, having an inverted funnel shape mouth formed at one end, a removable shank secured to one end of said member, a supporting block having a reduced portion located in said member, radially disposed pins 80 extended from said reduced portion of said block, gripping members arranged within said tubular member adjacent said mouth adapted to move into receptive positions by a member to be introduced through said mouth, each of said gripping members being loosely mounted on a respective pin, said tubular member adapted to retain said gripping members on said pins, and resilient means 85 co-operable with said gripping members.

3. A gripping device comprising a tubular member, a reciprocal supporting block having a reduced end, a plurality of outwardly projecting pins extending from the reduced end of said block, a gripping jaw loosely mounted on each of said pins, said tubular member adapted to retain said jaws on said pins, and means provided in said member whereby said jaws will be moved towards each other when said block is moved in one direction in said member.

4. A gripping device comprising a tubular member, a reciprocal supporting block having a reduced end and a plurality of pins projecting from said reduced end, a gripping jaw loosely mounted on each of said pins, a resilient member bearing against said block, said tubular member adapted to retain said jaws on said pins, and means formed on said tubular member for moving said jaws inwardly.

5. A gripping device comprising a tubular member, a reciprocal supporting block having a tapered end, a plurality of pins extending from the tapered end of said block, a gripping jaw loosely mounted on each of said pins, a resilient member bearing against said block, said tubular member adapted to retain said jaws on said pins, means formed on said tubular member for moving said jaws inwardly, and tool engaging means formed on said block for engagement of a drawing out tool.

JOSEPH W. OBERBECK.
